LOOSE-LEAF BINDER

Alfred M. Martin, Park Ridge, Ill.

Application May 31, 1940, Serial No. 338,063

5 Claims. (Cl. 129—17)

This invention relates to loose-leaf binders of the staggered prong type having a pair of oppositely disposed angularly opening prong-holding parts for carrying loose leaves in echelons, the margin of each leaf in a series being exposed for visibility of data or the like thereon.

The invention is especially adapted for binders of this class in which the prong-holding parts are relatively shiftable for maneuvering the leaves to remove or insert a leaf in proper position in echelon.

Among other objects, the invention aims to provide an improved binder of this type having enhanced flexibility of function and purpose, together with relative simplicity of structure and operation.

More particularly this and other objects and advantages will be apparent from the following description, taken together with the accompanying drawings, in which—

Figure 1 is a plan view of a binder illustrating my present invention and showing the toggle parts in half-open position, the covers being broken away to save space and showing, by broken lines, two alternate selective longitudinal shifted positions of the binder parts indicated;

Figure 1a is a greatly reduced plan view of the binder of Figure 1 showing account loose leaves or the like held therein;

Figure 2 is a bottom view of parts of the binder shown in Figure 1, and being a section taken on the line 2—2 of Figure 5 on a slightly reduced scale with the covers omitted;

Figure 3 is a longitudinal section taken on the line 3—3 of Figure 2;

Figure 4 is an enlarged view of locking members shown in Figure 3 with parts in changed position;

Figure 5 is a cross-section of the binder similar to Figure 6 but showing the toggle parts in fully closed position and omitting the binder back finishing material;

Figure 6 is an enlarged cross-section taken on the line 6—6 of Figure 1;

Figure 7 is a view of parts shown in Figure 6 in an alternative position as when the partially open locking mechanism is being released;

Figure 8 is a view similar to Figures 5 and 6, but showing the toggle parts in fully open position;

Figure 9 is a fragmentary plan section on the line 9—9 of Figure 6 on a slightly reduced scale omitting the back finishing material and showing, by broken lines, one longitudinal selective position of the binder parts;

Figure 10 is a perspective view of half-open locking parts; and

Figure 11 is a view similar to Figure 9 but showing an alternative longitudinal selective position of the parts.

Referring in detail to the illustrative construction shown in the drawings, the two-part toggle device represented by the toggle parts 12 and 13, connected by a central hinge 14, is supported by the two-part binder back represented by the back sections 15 and 16, as on side hinges 17 and 18 (Fig. 6). In accordance with the present invention, the binder back sections 15 and 16 comprise upright portions 19 and 20 which carry the hinges 17 and 18 respectively and longitudinally extending base portions 21 and 22 respectively, these base portions being at right-angles to the upright portions and lapping each other to be movable into more or lesslapping relation as the toggle device is opened or closed.

These parts are advantageously of metal but each of the binder back portions 19, 21 and 20, 22 is desirably faced where it would contact a desk or table top, with a non-metallic finishing 23 and 24 respectively to prevent scratching. The usual covers 25 and 26 which may also be of metal but desirably finished with a non-metallic material similar to the finishing 23, 24, but not here shown, are preferably hinged to the toggle device parts 12 and 13 respectively as by the hinges 27 and 28.

It will be understood that the hinges 17, 18, 27 and 28 comprise the usual aligned hinge sleeves on the binder parts through which sleeves are passed the usual hinge rods, and, in accordance with the present invention, the central hinge 14 for the toggle parts 12 and 13 similarly comprises the hinge rod 29 which passes through aligned hinge sleeves 30 on the toggle parts 12 and 31 on the toggle part 13. These aligned hinge sleeves 30 and 31, however, unlike the sleeves of the other hinges mentioned, are spaced apart on the hinge rod 29 so that each of the hinge sleeves 31 is spaced an equal distance from the adjacent hinge sleeves 30, leaving the spaces 32 therebetween at each end of each of the hinge sleeves 31, so that the toggle part 13 may shift longitudinally when the binder is partially or fully open, a distance in either direction from the normal opposed position of the toggle parts as shown in full lines in Figure 1, either to the distant shift position shown as at 33 in broken lines or to the proximate shift position shown at 34 in broken lines.

To accommodate this shift in either longitudi-

nal direction, the usual opposed staggered prongs, a series of which 35 are carried by the toggle part 12 and another series of which 36 are carried by the toggle part 13, are normally spaced apart at equal distances throughout the binder as shown in Figure 1, and also to accommodate this possible shift in either longitudinal direction of the toggle part 13, the horizontal portion 22 of the binder back part 16 which carries the toggle part 13 has less length than the horizontal portion 21 of the binder back part 15 and is normally centered longitudinally of the portion 21 so that as shown in Figure 9 when the binder is in the position shown in Figure 1 with the toggle parts in normally opposed position there is a space 37 at each end of the back portion 22 having a longitudinal distance the same as the spaces 32 on the center hinge 14, and which space 37 may be taken up by the back portion 22 when the toggle part 13 and its supporting back part 16 is shifted to the proximate longitudinally shifted position shown in broken lines at 34, for example. Movement in the opposite longitudinal direction as indicated by the broken lines 33 is reciprocal to that shown in Figure 9, and is as shown in Figure 11.

To assist in guiding the back portion 22 in both its transverse and longitudinal slidable movements with respect to the back part 21 to accommodate relative movement of the toggle device parts either into more or less overlapping position of the prongs 35 and 36, or in longitudinal shift relative movement of the toggle parts, the binder back portion 21 may carry at each end a plate 38 welded as at 39 to the binder back portion 21 but inwardly offset therefrom as at 40 along a line defining the space 37 and receiving between it and the main back portion 21 the lapping back portion 22. For convenience in construction, this latter portion 22 may be formed separately of the back portion 20 and may be welded thereto as at 41, the back portion 20 having a short horizontal extension 42 for this purpose, the latter also serving to elevate the portion 22 slightly above the portion 21 so that these two parts are relatively movable in parallel adjacent planes. As will be seen from the drawings, the lapping back portions 21 and 22 have not only relative longitudinal movement but also relative transverse movement, to accommodate opening and closing of the toggle device, to greater or less overlapping relationship, the overlapping of these parts being at its minimum as shown in Figures 6, 9 and 11 when the toggle device is in half-open position.

As shown in the drawings and in accordance with standard practice, the toggle device parts 12 and 13 each comprise a plate bent along longitudinal lines somewhat in the form of a chair, and having a front portion 43 which carries the hinge sleeves 30 or 31 as the case may be, a seat portion 44 and a back portion 45, to which latter portion is here attached as by welding a prong-carrying plate per se 46 which carries the prongs 35 or 36 as the case may be. An auxiliary back plate 47 welded to the back portion 45 carries directly the toggle part sleeves for the hinges 27 or 28, as the case may be, the other sleeves for these hinges being carried by the covers 25 and 26 respectively, and this plate is desirably continued downwardly parallel with the front portion 43 so as to provide a box formation for the toggle parts, turned down portions 48 of the toggle parts at each end further defining their box-like character. Another hinge plate 49

welded to the hinge plate 47 carries the toggle part sleeves for the hinge 17 or 18 as the case may be, the other sleeves for these hinges being carried by the upright portions 19 or 20 of the back parts 15 or 16, as the case may be. The covers, being hinged to the toggle device apart from the hinges of the toggle device to the back sections, desirably cause some of the weight of the covers and leaves thereon to tend to maintain the toggle device in equilibrium in half-open position.

As clearly shown in the drawings, the standard toggle portions 45 and 46 are here, adjacent the hinges 27 and 28, serviceably and uniquely extended outwardly beyond the hinge so that when the covers are brought toward each other to close the binder, the toggle parts tend to be fulcrumed downwardly so as to move the prongs toward each other also into closed position to guard against spilling of the sheets.

When the binder back is in fully closed position as indicated in Figures 2 and 5, the parts are releasably so maintained by fully closed locking mechanism, including a hook 50 desirably one at each end of the binder, suitably secured within the boxing of the toggle part 12, and projecting therefrom through an aperture 51 in the portion 43 of the toggle part to be received through another aperture 52 in the portion 43 of the other toggle part 13 where the hook is engaged by a catch bar 53 (Fig. 2), this bar being spring-pressed into locking position by the coil compression spring 54 and being movable against the force of this spring to receive the hook under the influence of the cam nose 55 of the hook. The bars 53, one at each end of the binder, are desirably angled along a longitudinal line to slide in the corner between the inner faces of the toggle portions 43 and 44 of the toggle part 13, and are cut away as at 52a therein to register more or less with the apertures 52. For common movement the catch bars 53 may be connected by a strap 56 as by spot-welding 57, and one of the bars, in this instance the proximate one in Figure 1, is conveniently extended beyond the end of the toggle parts in a thumb-piece 58 which moves with the toggle part 13, the spring 54 and the release thumb-piece 58 thus serving both of the bars 53 as a unit, clips 53a guiding the locking bars 53 in their sliding movement.

In accordance with the present invention, in addition to the fully closed locking mechanism just described, I provide partially open locking means for the toggle device including a bridge member 59 on one of the toggle parts, in this instance the toggle part 12, the bridge member having a locking lip 60 engageable with a latch 61 on the other toggle part, this latch being so constructed and arranged as to yield in the direction of pull of the bridge member 59 (Figure 7) when release means is actuated, which pull will occur when it is desired to open the toggle parts from the partially or half-open position shown in Figure 6 to the fully open position shown in Figure 8. The latch 61 is floatingly carried by a rest piece 63, in this instance desirably in the form of a channel. The latch 61 is normally prevented from yielding in the direction of the pull of the bridge member by a detent 62 which enters the channel member 63, the detent by thus pressing laterally the lower end 64 of the latch prevents the latch from rotating on the channel wall at 65 to releasing position as shown in Figure 7. The latch whether under the influence of the detent 62

or not, is continuously pressed upon by a leaf spring 66 which restores the latch to upright position, as shown in Figure 8, for example, as soon as pull on the latch ceases. The thumb-piece 58 may conveniently actuate not only the catch bars 53 for the fully closed locking mechanism, but also the detent 62 as by having the detent formed integrally with a strip 67 secured at 68 as by spot-welding 68a to the catch bar connecting strap 56. The leaf spring 66 is desirably welded as at 69 directly to the inner face of the portion 43 of the toggle part 13, as best shown in Figures 2 and 3, so as to be independent of the strap 56.

As best shown in Figure 10, the channel member 63 has a pair of upper walls 70 which overhangingly abut shoulders 71 on the lower end 64 of the latch 61, thus floatingly retaining the latch in the channel, and these walls 70 may also be employed to spot-weld the channel member to the inner face of the portion 44 of the toggle part 13 in the corner where this portion adjoins the portion 43, a lateral wall 72 of the channel member being welded to the portion 43 at this point so that the upper end of the latch 61 may protrude through an elongated slot 73 in the toggle portion 44 to engage the lip 60 of the locking bridge 59 carried by the other toggle part.

The bridge member 59 may be carried by the toggle part 12 as by fingers 74 at the end of the bridge member opposite the lip 60 and which fingers pass loosely through apertures 75 in the toggle portion 44, and are then turned upward slightly thereunder as at 76. Between the fingers 74 is a tail 77 which passes through an aperture 78 in the toggle portion 44 and is perforated as at 79 to receive one end of a wire reed spring 80, the other end of which is anchored by a plate 81 on the inner face of the toggle portion 44 as by spot-welding 82.

The bridge member 59 is thus spring-pressed toward the latch 61 so that its lip 60 will tend to engage the latch when the other parts are in proper position therefor, and also so as to permit the lip 60 to be resiliently cammed over the edge of the latch 61, the reed spring 80 yielding momentarily for this purpose, the bridge member being desirably angled as at 83 so that in moving the prong-holding parts toward each other from the position shown in Figure 8 to the position shown in Figure 6 the lip of the bridge will first strike the latch and ride thereover into locking position, and will then lock the toggle parts against movement back to the position shown in Figure 8, unless and until the thumb-piece 58 be pressed to cause the detent 62 to move in the channel 63 away from the abutment with the lower end 64 of the latch 61 as in Figure 2, and to the position shown in Figure 4, so that the latch can rotate as shown in Figure 7 to permit its upper end to yield (but under the influence of the spring 66) in the direction of the pull of the bridge, the lip 60 then slipping away from the latch.

When the toggle parts are in half-open position, as shown in Figure 6, and when the toggle parts are in normal opposite relationship as shown in Figure 1, these parts are also locked against relative longitudinal movement by inter-engaging means on the bridge member and latch, represented in this instance by lugs 84 in the form of spaced apart strips welded to the under face of the bridge member and angular at their outer ends to lap and be substantially

co-terminous with the lip 60. The distance between the lugs 84 is just slightly greater than the dimension, longitudinally of the binder back, of the upper end of the latch 61, so that in the position of the parts last mentioned, the latch is abutted at each end by the lugs 84 which thus inhibit relative longitudinal movement of the toggle parts. The parts shown in Figure 10 are desirably case-hardened to minimize wear therebetween, and particularly where the upper corners of the latch engage the lugs, as shown in Figures 6 and 7.

When, now, the half-opening locking mechanism is released by pressing the thumb-piece 58, the prongs may be spread apart to fully open position as in Figure 8, and the toggle part 13 may then be shifted longitudinally of the toggle part 12 in either direction, as already described. Assuming that the toggle part 13 has been shifted to its distant longitudinal position as shown in broken lines at 33, Figure 1, the toggle parts may be brought again together into half-open position as shown in Figure 6 with the toggle part 13 still in longitudinally shifted position, the bridge 59 again engaging the latch 61 but, as best shown in Figure 10, with one of the lugs 84 riding on the latch. Thus the toggle parts are locked against further opening movement but are not locked against reverse longitudinal movement of the toggle part 13 to return the toggle parts to normal opposed position in the binder back as shown in Figure 1. In this movement the lug 84 and lip 60 ride together on the latch edge until the latch is centered between the lugs 84, whereupon the reed spring 80 urges the lip 60 directly into engagement with the latch between the lugs, the space between the lugs thus providing a notch 85 for the reception of the latch.

The spaced apart 86 and 87 of the binder back 40 finishing 23 and 24 which lap the binder back portions 21 and 22 along their longitudinal edges respectively in a common plane guard against scratching of the desk or other table top during manipulation of the binder through the 45 various relative positions of the binder back parts, and at the same time the overlapping character of the binder back portions 21 and 22 minimizes undesirable open spaces between the binder back parts when these parts are spread 50 apart to maximum spread apart position, as shown in Figures 6, 9 and 11, only a relatively small gap 88 occurring at each end of the binder in the maximum spread apart condition of the parts and no space at all in the closed position 55 of the binder back shown in Figure 5. Also the uninterrupted outer face of the binder back portion 21 affords a relatively large usable area for the placement of a label or other informative insignia, referring as, for example, to the nature 60 of the contents of a particular binder.

Advantageous operation of the binder is as follows:

The binder back may be laid on a desk or other table top as shown in cross-section in 65 Figure 5, and the covers opened to the positions indicated, at which time the binder may be used like an ordinary book, account leaves or the like 100 (Figure 1a) being held in the binder in echelons with exposed margins steppedly arranged longitudinally of the binder back by the prongs 35 and 36, the leaves being impaled thereon through perforations in their other margins for this purpose in a well known manner not necessary to be here further described.

Unlocking of the toggle parts from fully closed

position as shown in Figure 5 is effected by pressing the thumb-piece 58 to release the hooks 50 from the catch bars 53. As is also well known and need not be further described, if it be desired to make manual entries on the leaves, the toggle device may be opened to half-open position, as shown in Figures 1, 1a and 6, so as to cause the leaves to lie flatter, and thereupon the leaves on the left-hand side of the binder will be held by the prongs 35, and the leaves on the right-hand side of the binder will be held by the prongs 36, but these prongs being staggeredly overlapped for swinging the leaves thereon.

If now it be desired to insert an additional leaf in its proper place in echelon, some of the leaves on the right-hand side of the binder next adjacent to the position which the additional leaf is intended to occupy, are swung to the left-hand side of the binder. Then the half-open locking mechanism is unlocked by again pressing on the thumb-piece to release the latch 61 from the locking lip 60 of the bridge 59, which permits the prongs to spread apart to the position shown in Figure 8. Then the additional leaf is inserted on the prongs 36 in proper place in echelon, then the toggle part 13 is shifted longitudinally to its distant shifted position as indicated in broken lines at 33, Figure 1. Then the prongs are brought again into overlapping position by moving the toggle parts 12 and 13 toward each other whereupon the half-open locking mechanism including the latch 61 and lip 60 will again engage to hold the prongs in the overlapped position shown in Figure 6. At this time since the toggle part 13 is still in longitudinally shifted position as indicated by the broken lines 33, the engagement of the latch 61 with the locking lip 60 will be as shown in Figure 10 in which the lip 60 is riding on the latch 61 through the intermediation of one of the lugs 84. The toggle parts are thus locked against relative rotative movement which might permit the prongs to separate from overlapped position, but the toggle parts are not locked against relative longitudinal movement. Next the leaves which had been swung to the left-hand side of the binder are swung back to the right-hand side while the toggle part 13 is still in shifted position as shown at 33. Next the toggle part 13 is shifted longitudinally back to normal opposite position with respect to the toggle part 12 as indicated in full lines in Figure 1, the latch 61 thereupon riding off of the lug 84 and into the notch 85 between the two lugs 84 and locking the toggle parts both against relative rotative movement which would permit the prongs to separate, and against longitudinal shifting movement, which might displace the leaves from their proper positions in echelon. The additional leaf is now located in its proper position.

Conversely, if it be desired to remove a leaf, the binder back being again in the position shown in Figures 1, 1a and 6, the leaves on the right-hand side of the binder next adjacent the leaf to be removed, are swung to the left-hand side of the binder, the thumb-piece pressed to release the half-open locking mechanism and to permit the prongs to separate, the leaf to be removed taken off the right-hand side of the binder, the toggle part 13 shifted longitudinally but this time to proximate shifted position, as indicated in broken lines 34, Figure 1, the prongs brought together into overlapping position by rotating the toggle parts to again lock the half-open locking mechanism (at which time the latch 61 rides on

the lip 60 through the intermediation of the other lug 84 opposite to the one shown engaged with it in Figure 10), the leaves which had been swung to the left-hand side of the binder are swung back to the right-hand side of the binder, and the toggle part 13 shifted back to normal opposite relation with the toggle part 12, whereupon the latch 61 again slips into the notch 85 to hold the toggle parts against both relative rotative separating movement and relative longitudinal shifting movement. It will be noted that the longitudinal shift of the binder part 13 in either direction is to a distance whereby a leaf in said series of leaves 100 say, may be shifted longitudinally of the binder a distance substantially equal to its exposed margin to insert or remove a leaf intermediately in the series.

It will be understood that during the longitudinal shifting movements of the toggle part 13 as just described, the binder back part 16 and cover 26 move with the toggle part 13 as are also shown in broken lines in Figure 1 at 33 and 34 respectively, showing the alternate selective shiftable positions and as shown in broken lines in Figure 9 and in full lines in Figure 11.

Since the latch 61 yields when released as described in the direction of pull of the bridge member 59, the weight of the leaves in the binder, which it will be understood is considerable when the binder is fully loaded, is prevented from placing a tension upon locking parts 60 and 61 which has been found in prior locking devices to make difficult the release of the locking mechanism.

The importance of the features of simplicity of structure and ease of operation of the present binder will be appreciated when it is understood that binders of this type are commonly made in large sizes and are most frequently handled and used by young women clerks.

Manifestly, the invention is not limited to details of construction shown for purposes of exemplification. Furthermore, it is not essential that all features of the invention be used conjointly, as various combinations and sub-combinations may be advantageously employed.

Having described my invention, I claim:

1. In a loose-leaf binder, the combination with a two-part prong-holding toggle device, of a two-part binder back supporting the toggle device, the toggle device being hinged to the back, each part of the binder back having an upright portion hinged to the toggle device and a longitudinally extending base portion at substantially right-angles to the upright portions, the base portions lapping each other and movable laterally into more or less lapping relation as the toggle device is opened or closed, interconnected means for guiding one part of the back and its supported toggle part both for movement toward and from the other part and also for limited longitudinal movement, and a pair of covers hinged to the toggle device apart from where the toggle device is hinged to the back.

2. In a loose-leaf binder, the combination with a two-part prong-holding device, of a two-part binder back supporting the device, each part of the binder back having an upright portion hinged to the device and a longitudinally extending base portion at substantially right-angles to the upright portions, the base portions lapping each other and movable laterally into more or less lapping relation as the device is opened or closed, and interconnected means for guiding one part of the back and its supported device part both

for limited movement toward and from the other parts and also for limited longitudinal movement.

3. In a loose-leaf binder, the combination with a two-part prong holding toggle device, the parts of the toggle device being arranged for limited relative longitudinal movement on a medial hinge, of a two-part binder back supporting the toggle device, each part of the binder back having an upright portion hinged to the toggle device and a longitudinally extending base portion at substantially right angles to the upright portions, the said base portion on one of the back parts being slightly offset to be in an adjacent plane parallel to and above said base portion on the other back part whereby the said base portions are adapted to overlap while having relative lateral movement limited by the toggle device and under the influence thereof, and a pair of keeper plates one at each end of the binder back secured to the second mentioned base portion and offset therefrom to a plane parallel to and overlying the first mentioned base portion whereby to guide the base portions in their relative movement, said first mentioned base portion also being shorter longitudinally than the said second mentioned base portion and the said keeper plates extending longitudinally beyond the said first mentioned base portion whereby to guide the said base portions also in relative longitudinal movement.

4. In a loose-leaf binder of the class described, the combination with a two-part prong holding toggle device having a medial hinge, of a two-part binder back supporting the toggle device, each part of the binder back having an upwardly extending portion hinged to one part of the toggle device and a longitudinally extending base portion fixedly angularly related to the upwardly extending portion, the base portionslapping each other and movable laterally into more or lesslapping relation as the toggle device is opened or closed, the toggle device parts having

5 limited relative longitudinal movement on the said medial hinge, and the toggle device part moving longitudinally with respect to the other toggle device part being arranged to carry with it in said longitudinal movement its respective supporting back part portion, interconnected means on the back parts for guiding the said parts in response to relative movement of the toggle device parts on the medial hinge, and a finishing part carried by each binder back part lapping the base portion along the longitudinal edge of the binder back, the finishing parts lying in a common plane and spaced apart medially of the binder back whereby to permit said relative movement of the said back parts.

10 5. In a loose-leaf binder, the combination with a prong-holding toggle device having a medial hinge and two relatively angularly movable parts, of a two-part binder back supporting the toggle device, each part of the binder back having an upright portion hinged to one part of the toggle device and a longitudinally extending base portion at an angular relation to the upright portions, the toggle device parts having limited relative longitudinal movement on the said medial hinge, and the toggle device part moving longitudinally with respect to the other toggle device part being arranged to carry with it in said longitudinal movement its respective supporting back part portion, means on the back parts lapping each other and relatively movable laterally as the toggle device is opened or closed and the back parts move relatively laterally at least partially responsive to the relative angular movement of 20 30 35 said toggle device parts, and interconnected means for guiding one back part and its supported device part for said limited longitudinal movement with respect to the other back part and the supported device part of the latter back part.

ALFRED M. MARTIN.
